UNITED STATES PATENT OFFICE.

EDWIN F. NORTHRUP, OF PRINCETON, NEW JERSEY, ASSIGNOR TO THE AJAX METAL COMPANY, OF PHILADELPHIA, PENNSYLVANIA, A CORPORATION OF PENNSYLVANIA.

METHOD AND APPARATUS FOR ELECTRIC HEATING BY HIGH-FREQUENCY CURRENTS.

1,286,394.

Specification of Letters Patent.

Patented Dec. 3, 1918.

Application filed September 19, 1917. Serial No. 192,048.

To all whom it may concern:

Be it known that I, EDWIN F. NORTHRUP, a citizen of the United States, residing at 30 Wiggins street, Princeton, in the county of 5 Mercer and State of New Jersey, have invented a certain new and useful Method and Apparatus for Electric Heating by High-Frequency Currents, of which the following is a specification.

10 The primary purpose of my invention is to transfer electric energy into a continuous mass by electromagnetic induction and there to convert the electric energy into thermal energy in such mass by means of high 15 frequency currents and without the whole or partial interlinkage of a ferro-magnetic with an electric circuit. The high frequency currents may be intermittently supplied, being damped out proportionally to the rate of 20 energy consumption or the high frequency current may be sustained by continuously supplying energy at a rate equal to the rate of energy consumption.

A further purpose of my invention is to 25 take advantage of the enormous rate of change of high frequency currents in induction furnace work to eliminate necessity for a whole or partial interlinkage of a ferro-magnetic circuit with an electric circuit.

30 A further purpose of my invention is in a heating system, to heat masses for the purpose of melting them or heat-treating them or preparing them for work by other processes, (all herein generically referred to as 35 electric furnaces) by means of the heating effect of electric currents having the natural frequency of an oscillating electric system, having either damped or maintained oscillations, as contrasted with the forced frequency directly produced by alternators.

A further purpose is to tremendously increase the rate of change of reversed electromagnetic induction in electric furnace work by applying thereto free oscillations of 45 electricity.

A further purpose is to make available interchangeably for electric furnace operation either a resonant circuit having maintained oscillations or the discharge of a condenser, 50 the energy being impressed upon the circuit

in which the oscillations take place by different means such as for example, as by an alternating current generator with the frequency of which the oscillation current circuit is approximately in tune or by an alternating current generator merely charging the condenser as desired. 55

A further purpose is to heat a resistor by circulation of high frequency currents within it through action of electric current induced as distinguished from hysteresis and without necessity for iron interlinkage. 60

A further purpose is to make an electrically conducting but desirably not paramagnetic resistor which is to be acted upon 65 the secondary of a primary comprising one or more inclosing or contiguous oscillation coils and discharging a condenser or condensers through this primary to induce currents of corresponding period within the resistor without requiring interlinkage of iron 70 to secure the transfer.

A further purpose is to pass maintained free oscillations or current about a resistor in a heating system, securing continuous 75 transfer of current, and thus of heat, to the resistor.

A further purpose is to approximately tune an oscillating circuit for an electric furnace to a high frequency alternating current 80 supply circuit by which the energy is supplied.

A further purpose is to produce an electric furnace which takes a leading current, enabling me to use the lagging current, 85 usually available, to advantage and to compensate by positive reactance so as to secure unity power factor.

A further purpose, where a liquid or molten conducting pool forms the resistor, is to 90 secure stirring by the same induced current that causes the heating.

Further purposes will appear in the specification and in the claims hereof.

I have preferred to illustrate my invention chiefly diagrammatically, in view of the broad character of the invention, and have applied it to but one art and to but two illustrations in that art, among the various arts and many forms in which it may be car- 95 100

ried out, selecting therefor an art which is important and forms which are practical, efficient and simple, in which my invention has high commercial utility and which at 5 the same time illustrates the principles of my invention to considerable advantage.

Figures 1 to 6 are diagrammatic views illustrative of my invention.

Figs. 7 and 8 are diagrammatic views 10 showing in a more or less hypothetical way the directions of flow of induced currents of electricity and of a molten resistor when my invention is applied to furnace operation.

Fig. 9 is a sectional view showing one application of my invention, there applying to 15 a vacuum crucible furnace.

In the drawings similar numerals indicate like parts.

My invention as illustrated applies oscillatory electric currents to the heating of conducting material. My invention resides both in the general application of the principles involved and in the processes and apparatus by which these principles are utilized 20 in the particular art from which I have taken my illustration.

The introduction of inductance into the circuit of an alternating current transmission line under "forced vibration" causes 30 the current to lag in phase behind the electromotive force, and capacity so introduced causes the current to lead in phase. The preponderance of induction over capacity both in the line and in the coils of existing 35 induction apparatus applying heat has reduced the power factor making it prohibitively low in otherwise desirable installations. With a relatively small amount of power available for use, this low power 40 factor requires an equipment in proportion to the relatively large currents flowing in the line and heat is developed where it is not only not required but even injurious.

If, on the other hand, electric energy be 45 applied to a circuit containing a condenser and the latter be then allowed to discharge itself through a closed circuit, the electricity oscillates back and forth like a pendulum.

If the oscillations be damped proportionally 50 to the rate of dissipation of energy, as would be the case when the condenser is charged and discharged through a gap without provision for maintaining the amplitude, the oscillations reduce in amplitude 55 until the energy stored in the condenser is finally dissipated in electric radiation and in heat. In this form the effective transfer of energy takes place intermittently, during a part only of the time. For each discharge 60 and recharge, the discharge takes place during a part only of the total time, the time of recharge being relatively wasted.

Where the circuit is a resonant one, (which may, nevertheless, contain a discharge gap)

the oscillations are "maintained", i. e., are 65 of the same amplitude at all times by reason of continuous supply of energy in proportion to the rate of energy transfer. They also oscillate continuously, and energy transference takes place throughout the entire 70 time.

In the first (damped) form the inductance of the circuit does not affect the total energy transformed, only the natural frequency, the time within which the oscillations will cease (the damping factor) and the number of oscillations. In the resonant circuit the inductance does not affect the total energy transformed but must be proportioned to the capacity of the other 80 branch so as to tune the circuit to the frequency of the alternating current supply.

The inductance in the "damped" form is comparable with the mass of a ball swinging at the free end of a spring whose opposite end is fixed. There is no dissipation of energy in this mass and its increase merely alters the period of the vibration. the time within which the spring comes to rest and the number of vibrations of the 90 spring. If the ball be given sufficient impulse throughout each oscillation to maintain the same amplitude, so that the spring does not come to rest and the oscillations become continuous, this comparison applies 95 to the resonant circuit having maintained oscillations.

If the capacity and inductance be large, the fraction of energy dissipated in radiation is negligibly small. The movement of 100 electricity in the circuit constitutes a natural, unforced or free vibration having a period

$$T = 2\pi\sqrt{LC}$$

105

where C is the capacity and L the inductance of the circuit.

In the damped form, since T should be less than the period of the alternating current supply and in practice is therefore 110 limited, the product of $L \times C$ must be kept within limits. This can very readily be done for any total values of capacity and inductance by placing the condensers in multiple or splitting up the oscillation coil 115 into parts fed from different condensers, which may be placed in multiple, by special non-inductive line construction and in other ways.

In the illustration having sustained oscillations and a resonant circuit the period becomes the same or nearly that of the alternating current supply and the tuning of the circuit is, of course, dependent upon this 120 agreement.

It might be noted that the currents in an oscillation resistor subjected to the influence of the impulses correspond to those in the 125

oscillation coil in period and follow the fluctuations of the oscillatory currents even though they be not themselves of free vibration.

- 5 The only points or places in such a free oscillation circuit where heat is dissipated are where there is ohmic resistance or where there is an inductively coupled circuit having ohmic resistance, such as a solid, liquid 10 or plastic body of conducting material or container or holder therefor forming a secondary to such a free oscillation primary.

The oscillation circuit can be transmitted a considerable distance from the location of 15 the condensers with low heat losses and converted at the distant point almost wholly into heat. The conversion will comprise an "integration" of the impulses in the oscillation resistor corresponding to the oscillation 20 or oscillations in the inductor coil.

As the energy stored in the condenser is one half its capacity times the square of the voltage to which it is charged, the sole determining factors for the available energy 25 from a single charge are the size of the condenser and the voltage applied in charging it. The power is then determined by the number of times the condenser is charged to this voltage and discharged per unit of time. 30 The inductance of the circuit, the resistivity of the metal constituting the secondary coupled circuit or resistor and the closeness of the coupling have no effect upon the power generated and, theoretically, no 35 effect upon the power delivered to the resistor.

Discussing now the first form, having damped oscillations:—

Where the available voltage is sufficient 40 to charge the condenser directly from it, no transformer is required between the supply and the condenser and I have shown such a construction in Fig. 1. The theory will be well understood from this figure. A single 45 phase alternating current circuit is shown having sides A, A'. The condenser to be charged is shown at C, the oscillation coil, through which the condenser discharges, at O, the inductance of the two sides of the circuit at L_1 , and L_2 , L_4 and a discharge gap 50 at G. These inductances are intended to represent the entire inductance of each side of the circuit and are divided for convenience in the later discussion.

55 The energy stored at each charge is $1/2 CV^2$. When the discharge gap G breaks down, the energy will surge in the oscillation circuit until it is all dissipated in radiation and heat, for low frequencies almost entirely in heat.

The means of dissipation are as follows:

1—Dielectric loss in condenser.

2— I^2R loss in discharge gap G.

3— I^2R_1 loss in line, where R_1 is the ohmic

resistance of the line possessing inductance L_1 and L_2 .

4— I^2R' loss where R' is the ohmic resistance or its equivalent of that portion of circuit where it is desired to convert the energy $1/2 CV^2$ into heat.

5—Radiation loss. This is the radiation of energy utilized in radio telegraphy and is quite negligible for low frequencies and especially for non-linear, non-open circuits here used.

6—Losses in the transformer D which feeds the oscillatory circuit.

It is indifferent whether R' is a resistance located in the oscillatory circuit or whether it is a resistance in an inductively coupled circuit, i. e., in the oscillation resistor, or the sum of these; and because the secondary circuit constitutes but a single turn within the mass and the inducing circuit has several turns, the magnitude of the current in the oscillation resistor is correspondingly great.

In speaking of the "mass" I desire to make clear that, though in some uses of my invention the oscillation coil may operate upon a thick mass, such as a billet, bloom or other unit of metal to be worked, the shape may vary widely according to the application intended and may be, for example, a mere shell of cylindrical or other shape, the resistor being permissibly solid, in paste form, molten or normally liquid.

The oscillation coil O in the illustration happens to form a part of two circuits. It is part of the alternating circuit for charging of the condenser and also constitutes an oscillation primary in the discharging circuit for the oscillation resistor as a secondary.

In the effort to transmit the energy stored in potential form in the condenser to the conducting material heated with maximum efficiency, it is indifferent, within wide limits, what may be the natural frequency of the oscillatory circuit. I have obtained substantially equal frequencies with 25,400 110 cycles and 12,500 cycles per second, respectively. The efficiency which we wish to get is

$$E_t = \frac{p}{P}$$

115

where p is power dissipated and held as heat in the oscillation resistor and P the power supplied at the primary terminals of the transformer.

To obtain high efficiency the following 120 losses must be small:

1—Dielectric loss. (Low frequency of oscillation will contribute to make this loss small.)

2— I^2R_1 loss in discharge gap.

3— I^2R_1 loss in line. To make this loss small the ohmic resistance of L_1 , L_2 , L_3 and L_4 must be kept low.

If L_1 and L_2 are large (which does not affect power) and their ohmic resistance is negligible they will not diminish the power transmitted in the oscillation circuit while the potential drop will take place chiefly over them, so that the potential drop at the ends of the oscillation coil O , can be kept comparatively low. This will facilitate insulation between the coil and its secondary.

With each surge of the oscillatory current through the coil circuit, there will be a tendency of the supply current to short circuit through the ionized air across the discharge gap. This may be controlled by the inductance L_3 , L_4 , of the supply circuit or by other means, such as blowing out the discharge.

Since the supply of alternating current will seldom agree in voltage with that desired to charge the condenser, the circuit will more usually be as indicated in Fig. 2, where the supply circuit A , A' , is transformed at D and the condenser is charged from the secondary transformer connections a , a' .

While the short circuiting of the supply, (here taking place in the secondary) across the discharge gap, can still be controlled by primary inductance, or by special provisions for blowing or vacuum at the discharge, it is more desirable to control it by inductance in that portion of the circuit between the discharge gap and the transformer secondary, indicated diagrammatically at l_3 , l_4 . The discussion of Fig. 1 is then applicable to this form also with the change in symbols from A , A' , to a , a' , and L_3 , L_4 , to l_3 , l_4 . In Figs. 1 and 2 the oscillation coil may be placed in the discharge gap connection, free from the charging circuit, if desired.

I have shown different resistors in the two figures, the resistor W' in Fig. 1 being the molten, or otherwise liquid electrically-conducting content of an electrically non-conducting crucible 11, whereas the resistor in Fig. 2, shown at W^2 , is a bloom or billet of metal which is to be worked.

In Figs. 3 and 4 I have illustrated my invention as applied to a multiphase circuit without unbalancing the phases, selecting two phase for the illustration because it presents the simplest form and, therefore the form capable of easiest clear explanation.

Because transformers will be required usually to step-up the voltage from that available to the much higher voltage under which my invention becomes most efficient, I have shown transformers here, the system being practicable wherever two phase current may be obtained. The transformers can be omitted where the commercial current is of suitable voltage.

The two phase primary circuit has sides A , A' , and B , B' , connecting with the primaries respectively of transformers D , D' . The secondaries of these transformers are

shown as united at N . The other secondary terminals and the neutral are connected to opposite sides of respective condensers C , C' , which are arranged to discharge through any suitable discharge gaps G , G' . It will be seen that the discharge circuits do not include the secondaries of the transformers.

At some suitable point or points in the discharge circuit I place an oscillation coil or coils shown as O , and O' , which form the heating coils for the furnace or (as shown in Fig. 3) for two furnaces and may surround a single resistor or, as shown, separate resistors which may here, for illustration, be either electrically conducting crucibles 11, $11'$ or their contents, W^3 if the latter be electrically conducting. There is some advantage in placing coils within the separate circuits in the figure shown instead of using one coil within the neutral connection, in that the form shown protects against loss of effective energy through discharge of the condensers and gaps in series, which discharge would not pass through a heating coil placed within the neutral connection.

My furnace takes a leading current; i. e., the secondaries of the transformers, or the primary current supply where there are no transformers, leads into an initial negative reactance. Most commercial circuits have a lagging current and my furnace can be connected with such a supply to great advantage, adjusting by positive reactance to balance the lag of the supply current and the lead of the furnace current and secure unity power factor. I have illustrated connections for this in Fig. 4, where the circuits are intended to correspond generally with Fig. 3, except that adjustable positive reactances L_5 , L_6 are included in the primary supply for the purpose indicated. The coil windings in the two circuits are shown as surrounding the same resistor W^4 ; (which may be any species of the resistor W), and as continuous, with a tap at the middle from the neutral connection. The adjustable reactances could, of course, be placed within the secondary windings instead of within the primary as shown.

The user can often purchase power more cheaply for supplying a load that has an initial leading current.

I purpose using alternating current supply and I desire to be understood as including in this term such makeshifts or substitutes as charge condensers without actually using alternating currents, regarding these substitutes as electrical equivalents of the alternating current for this purpose.

Obviously current supply of the required potential could be connected directly to the lines instead of through the transformers shown.

Where there is no resonance, and the condenser and discharge gap are used to provide

free oscillations, the frequency of the primary circuit is not of primal importance though the rate of discharge and the voltage of the current passing through the discharge circuit are important since they affect both the number and the rate of succession of the impulses.

In the use of multiphase supply it will be noted that the discharge from different condensers is likely to occur at different times since they are charged by currents of different phase. In operation the multiphase electromotive forces are impressed on the primaries of the two transformers and the condensers are charged to a break down potential with the discharge gap adjustment used. As each discharge gap breaks down the oscillatory current surges through the oscillation coil or coils which, acting as a primary will induce oppositely directed current flow in resistor W, forming the oscillation secondary. The secondary flow is in substantially parallel planes or strata to that in the inducing oscillation coil.

With the very great rate of change of current flow, secured by high frequency, due to the rapidity of the reversals, the electric impulses transmitted to the resistor are very large without the necessity for interlinking any magnetic circuit with the resistor circuit. I believe that I am the first to produce effective electric heating by induction without the interlinkage of a magnetic circuit, by which I mean a ferro-magnetic circuit, and that I am also the first to beneficially apply high frequency currents of any character to the electric heating art. It will be noted that my invention does not depend upon the hysteresis of magnetizable material nor upon the use of a magnetically permeable core, casing or resistor, but requires only that the material to be acted upon or an ancillary mass or container in suitable heat-transferring relation to it shall be a conductor of electricity.

The successive chargings of the condensers will alternate, as will also their discharges, at intervals depending upon the capacity of the condensers, the applied voltage and the extent of separation of the discharge gap, resulting in a rapid series of heating electric impulses within the resistor which, when applied to a liquid or molten resistor tend to stir the resistor. The current density in the metal may be made great enough to produce effective stirring. The stirring and the rate of heating are both proportionate to the rate of energy input in a given volume of resistor.

The rate of input is of course dependent upon the number of alternations. In my own operation of the invention I have used thousands of alternations per second with great success.

In order that the broad character of my

invention may be made clear and that it may not even seem to be restricted to application to a single form through the accident of illustration by that particular form among various embodiments in which those skilled in the art will be quick to grasp its usefulness, and without intending to suggest any limitation to the general types of which these two form illustrations, I will describe a second application of my invention, which differs from the first in that the furnace circuit is tuned to the extent that the supply current is nearly in phase with its voltage in agreement with a high frequency and preferably high voltage supply, so arranged as to secure the advantage of condenser action without the necessity for discharge gap use though permitting discharge gaps to be inserted if desired. By this arrangement I secure an uninterrupted series of oscillations, each of full amplitude.

It is my purpose to include in this application claims covering broadly the application of high frequency currents to electric heating; and to the transfer of electric energy for conversion into heat within a resistor through electromagnetic induction and without need of partial or complete interlinking of transformer iron or like paramagnetic material with an electric circuit to effect the conversion; as well as upon oscillation current discharge through a coil for heating purposes, taking claims for that purpose from my copending application, Serial No. 133,474 for oscillation current method and apparatus, filed November 25, 1916. I plan to claim specifically in that case subject matter which is not claimed in this application and to claim within this present application in addition to the broad subject matter indicated, the form herein-after described using a resonant circuit.

It is my purpose to transfer also to this application, claims now pending in my application for oscillation spiral coils and connections filed June 18, 1917, Serial No. 175,519, upon subject matter relating to the provision of a furnace circuit taking a leading current, or having a negative reactance, and the supplying of positive reactance whereby unity power factor may be obtained when my circuit is connected with supply circuits having the usual lagging current.

In the second form of my invention, illustrated diagrammatically in Fig. 5 and by vector diagram in Fig. 6, I supply current from any suitable alternating current source of supply, shown as an alternating current dynamo H, which preferably gives high voltage directly or through the medium of a transformer and at high frequency and requires but a small supply current for the power furnished. I apply the cur-

rent at points p p' upon opposite sides of a condenser C^2 , here shown to be adjustable, in a circuit exactly or approximately tuned to the frequency of the generator circuit 5 and containing the condenser in one branch and an inductance L_7 in the other. The inherent resistance of the two circuits I have represented as r and R respectively. The current in the generator circuit is represented as I , that in the branches as I_c and I_1 , the electromotive forces in the generator circuit and in the several parts of the inductance circuit as E , E_r and E_x and the equivalent resistance of the part of the 10 circuit at L_7 as X_1 , respectively.

The inductance coil L_7 is a furnace coil and may be made to operate upon any resistor as freely as any of my other furnace coils. With the connections shown, relatively 20 large currents flow within the condenser and inductor coil (furnace) circuits.

The current values in such a circuit having assigned constants and without tuning have been indicated in an example given in 25 Bedell & Crehore on *Alternating Currents*, 3rd edition on pages 308-310, showing the currents in the two branches to be greatly in excess of the current in the supply circuit. It will be recognized that the currents there 30 in are out of phase with the voltage of the supply, one leading the electromotive force and the other lagging behind it.

No discharge gap is required and the advantage from one is at least questionable. 35 Obviously one could be inserted, if otherwise desirable, without rendering the apparatus or method inoperative. Any assigned advantage from an intended discharge gap would merely be compared with its inherent energy loss to determine the advisability of inserting it.

Taking up the vector diagram, Fig. 6:— Because the resistance r is negligible the current I_c may be plotted ninety degrees 45 in advance of the electromotive force and its value may be fairly considered $I_c = E^2 NC$.

The resistance and current in the inductive branch (or the equivalent inductive coupling of the resistor heated by the coil) 50 determines the value of the E. M. F. component E_r which lags behind the electromotive force nearly ninety degrees. The value of the current I_1 is given by the following relations; this current being in phase 55 with E. M. F. component and 90° behind the E. M. F. component E_r .

$$I_1 = \frac{E_x}{R} = \frac{E}{X_1} = \frac{E}{\sqrt{R^2 + (2\pi NL)^2}} \cdot I = \sqrt{I_1^2 - I_c^2}$$

60 because

$$I^2 I_c^2 = I_1^2$$

The power supplied by the source of electromotive force is

$$P = EI = E \sqrt{I_1^2 - I_c^2}$$

65

A condition of approximate tuning in the circuit is preferable to exact tuning, as true resonance would cause the current I to slightly lead the electromotive force E as distinguished from exact phase relation 70 as illustrated in this diagram, not a serious difference.

From the equation

$$P = E \sqrt{I_1^2 - I_c^2}$$

75

it will be seen that a high electromotive force may be used to great advantage here since the supply current may be reduced to very small values. I_1 and I_c may closely approximate each other in value.

80

Again since the value of E_r is plotted as a chord within a circle having diameter E it can be seen from the vector diagram that the angle of lag of I_1 behind E will decrease with increase of E_r , i. e., with increase of the closeness of inductive coupling between the resistor and the furnace coil; showing that as inductive coupling between the coil and the resistor increases, and consequent increased work is done, the 90 dynamo will be called upon to supply correspondingly more power.

85

One advantageous use of high electromotive force and low current values is to accommodate this method to inexpensive dynamo construction and low transmission losses where the current is transmitted any considerable distances.

95

As a result of the approximate tuning to the frequency of the supply circuit the oscillations from the condenser discharge are continuously accelerated in proportion to the drag, retardation or damping to which they are subject during their oscillation because of the transfer of the energy to the 100 resistor, so that the full maximum amplitude and strength of these oscillations is maintained as distinguished from the rapidly reducing amplitude and strength of the damped oscillations used by me in my 110 method described in connection with Figs. 1-3.

105

Since there is no interruption of the oscillations while the condenser is being charged in this form of Figs. 5 and 6, energy is 115 transferred at the maximum rate above indicated, during the entire time as compared with the discharge interval only (out of a much larger time taken for charge and discharge) in the process described by me in 120 connection with Figs. 1-4.

115

By this method I estimate that for equal sources of power supply I can use condensers of about one-fifth of the bulk or weight that I find necessary to use with the 125 form of my invention first described.

120

These two advantages make it possible to greatly increase the energy input with a given bulk of condenser as compared with the energy input possible by means of my 130

first-described form, and to supply the energy at a high voltage which is applied to the circuit with or without intervening transformers according to the voltage desired, obtaining large current flow without appreciable reduction in voltage.

It will be evident that the oscillations produced by this second form of my invention are in a broad sense "free" oscillations, notwithstanding that they are "maintained" in amplitude and continuous in time, since their periods and maximum amplitudes are largely determined by the electrical constants of the condenser and inductor branches of the circuit and the frequency agreement with the supply circuit, being the result of selection of these constants and not of agreement "forced" by the dynamos or other source.

With the tuned circuit, having the amplitude of its oscillations maintained, the intervals will depend upon the rate of change of the electro-magnet impulses applied to the resistor which will depend upon the frequency of the supply circuit, placing a premium upon high frequency supply.

The adaptation of my second form to multiphase operation without unbalancing the phases is sufficiently obvious not to require illustration but does not offer quite the same advantage as in my first form if a special generator be used. This generator may be driven conveniently by a multiphase induction motor, permitting single phase to be supplied by the generator without unbalancing.

My furnace is applicable to a great variety of heating applications including the heating of a mass of metal or other material, in itself conducting, without regard to irregularities in shape and permitting local application of the heat to a particular belt or section or even to a spot contiguous to the end of the coil upon the surface of a resistor as well as to furnaces having crucibles, conducting or non-conducting, for handling finely divided material or other material to be heated, melted or smelted. It lends itself particularly to crucible furnaces because the resistor may be in a compact mass, as no interthreading of magnetic circuit interrupts its continuity and no circulation tubes are required. This permits convenient and effective heating in vacuum as in Fig. 9, since with all forms of my invention the heating coil need merely surround that form of crucible most convenient and the crucible may be designed with special reference to vacuum maintenance.

In this figure any suitable coil 10 here shown as helical, surrounds a container 12 fitted with an air tight top 13 through which a tube 14 leads to a vacuum. Within the container a crucible 11^a is placed, supported

upon sand or other filling 15 to bring it 65 to the right height with respect to the coil, to suit the size of crucible and the depth of content 16 in it. Either the crucible or the content may be the resistor.

The oscillation current, passed through 70 the coil by reason of whatever circuit connections, induces current flow in the resistor in planes parallel to the planes of the coil. Skin effect causes the induced current to be somewhat more concentrated in an outer 75 portion of the resistor than in other parts, heating the outer perimeter more rapidly than the inner portion and providing a correspondingly large conduction area for transfer of heat to the inner part of the 80 resistor. Joule effect is also present. The direction of current flow in the oscillation coil is indicated by the outside arrows in Fig. 8, the inside arrows indicating the direction of induced current within the pool. 85

By proportioning the cross section of a molten or otherwise liquid resistor to the current the latter may be made great enough to develop "pinch" contraction of the current-carrying resistor giving effective stirring radially inward from the more highly heated outer part of the pool. The direction of the fluid flow is modified by the Joule effect. The effect of this is shown by the circulation lines in Fig. 9, the directions of 95 the impressed and induced current impulse being shown by the arrow points and tails in the circles just outside and inside the crucible walls. The stirring is not of the same importance as the transfer of energy 100 into heating of the resistor, because of the ready conduction of heat from the outside inward. This is especially true since the crucible content is the resistor and I deliver the heat directly within the main body of 105 the molten or liquid mass, but where desired may be made proportionate to the need, to maintain advantageous approach to uniformity of temperature.

It will be evident that each of the two 110 forms illustrated possesses advantages not possessed by the other. The form shown in Figs. 1, 2, and 3 is capable of use with existing commercial power circuits, whatever the frequency, with or without transformer use 115 according to the potential and without unbalancing multiphase circuits, and requires no extended outlay for apparatus other than the condensers and furnace. An effective and desirable inexpensive discharge gap for 120 such use has been practically developed by me and is disclosed in my application for patent for discharge gap, Serial No. 175,518, filed June 18, 1917. Relative disadvantages exist in that the discharge takes place during a part only of the total time, interspersed between charging periods, and that 125 the amplitude of the oscillation is reduced

by damping. This requires that the bulk or weight of condensers required is about five times as great as for the other case of sustained oscillations.

- 5 As the form shown in Figs. 5 and 6 requires a generator having a frequency not ordinarily attainable and requiring for its best operation, special construction, the current cannot be taken to advantage from existing power circuits. It has the advantage of avoiding the necessity for discharge gaps and of utilizing and maintaining continuous discharge having uniformly high amplitude and a high efficiency from a time standpoint 10 because of its continuous operation. It also obviates the need of a large bulk or weight of condensers.

In either event the simplicity of the furnace, and its freedom from irregularities of 20 shape and detached resistor parts makes it approach the ideal furnace, particularly when applied to crucible work in melting, refining or heat-treatment of materials.

The crucible form is easy to fill and empty 25 and the content can be chilled and again reheated without breakage of the crucible.

The resistor is heated as a mass and is less dependent upon circulation for the heating than in other inductive forms free from contamination by gases. Commercial frequencies of supply can be used with one of the 30 forms illustrated and without unbalancing polyphase circuits. Since the material heated is in a mass of approximately cylindrical form, the ratio of radiating surface to 35 volume is small and this greatly reduces heat losses.

The power factor may be maintained substantially at unity and the efficiency 40 markedly increases with increase of the size of the furnace.

It will be obvious that in both forms of my invention the effect is that of charging and discharging the condenser, even though 45 no charging time is lost in the second form.

The approximation to tuning in the claims as to my second form, is intended by me to include exact tuning also.

It will be evident that, from another viewpoint, the second form of my invention 50 might be considered as comprising an alternating current circuit which is feeding current into a furnace circuit having positive reactance and in which the normally low power factor otherwise resulting from the 55 positive reactance is corrected by capacity thrown across the positive reactance or across the generator terminals (with proper connections these would be substantially 60 equivalent) with the effect of balancing the positive reactance by the negative reactance of the capacity until unity power factor is secured in the supply circuit, or until there has been such an approach thereto for the 65 purpose desired that further perfection of

balance no longer justifies the rather careful adjustments required.

It will be further evident that under these circumstances the current in the local circuit through the capacity and furnace inductor coil will be substantially the same at all times, but quite different from that in the generator circuit. For example, a generator capable of supplying 100 k. w., operating at 12,000 cycles per second and delivering current at 6,000 volts, would supply 16 $\frac{2}{3}$ amperes in the generator circuit and 452 amperes in the furnace coil circuit, provided the capacity shunting the generator terminals is one microfarad and the inductance of the furnace coil is properly chosen so that the power factor for the generator circuit is unity.

If the furnace is absorbing no power, then 85 the current supplied by the generator is negligibly small, while the current through the furnace inductor coil remains substantially the same, the current in the inductor coil and the current flowing through the condenser being in this case different in 90 phase by almost exactly 180° and therefore almost wholly wattless.

As the demand from the furnace increases, this angle of nearly 180° is reduced 95 and the proportion of watt current to wattless current in the furnace inductor coil increased with corresponding greater demand upon the generator and larger current supply from it.

The impulses given by the two types of 100 current which I prefer to use, (the one oscillating with decreasing amplitude as it is damped and the other oscillating with the same amplitude, maintained by reason of the energy continuously supplied to it) have 105 both been called by me "free oscillations" and "oscillatory". These terms are intended to distinguish them from the forced oscillations delivered by an alternating current generator in some of my claims, as I intend 110 not to cover such alternating current also.

Having thus described my invention, what I claim as new and desire to secure by Letters Patent is:—

1. An inductor heating coil adapted to 115 heating a resistor and free from complete or partial interlinkage of transformer iron with the resistor in combination with high frequency current supply for the coil.
2. A non-magnetic mass to be highly 120 heated, an induction coil in operative relation thereto and a high frequency current supply for the induction coil.
3. In a heating system a hollow induction coil adapted to heating a resistor and means 125 for passing high frequency current through the coil.
4. In a heating system a hollow heating coil adapted to heating a resistor and free from partial or complete transformer mag- 130

- netic interlinkage therewith in combination with means for passing high frequency current through the coil.
5. A heating system having inductive transfer of electric energy at high frequency from the inductor element to the resistor, transformed into heat therein and free from transformer iron.
6. Induction heating mechanism comprising a hollow conducting coil providing a space within for a resistor adapted to receive successive materials to be heated and a source of high frequency current supply for said coil.
- 15 7. Mechanism for inductively treating a resistor, comprising a conducting coil, material to be treated in inductive relation thereto, a condenser, a charging source of current for said condenser and connections 20 for discharging the condenser through the coil.
8. In a heating device, a container for a liquid pool, a conducting coil adapted to surround said pool, a condenser connected to 25 discharge through said coil and means for successively charging and discharging said condenser.
9. In a heating device, an electrically conducting coil, an electrically non-conducting 30 container therein adapted to hold material in molten ore liquid form and free oscillation current supply for said coil.
10. In a furnace, an alternating source of current supply of high frequency and 35 branched circuits to which it is connected, having respectively capacity and a heating coil providing inductance, the capacity and inductance being proportioned to form a circuit of the branches approximately resonant 40 with the alternating current supply.
11. In a furnace, an alternating current source of supply and a divided circuit to which it is connected and in approximate resonance with the supply and having a furnace coil in one branch of the divided circuit.
12. In a heating device a high frequency alternating current source of supply and a divided circuit connected therewith having 50 capacity and inductance in its respective branches proportioned to bring it into approximate tune with the source of supply and including in the inductance a heating coil.
- 55 13. A heating coil providing inductance, a condenser in circuit therewith and a high voltage alternating current source of supply to which the circuit is approximately tuned and connected with the circuit across 60 the condenser terminals.
14. A high frequency high tension alternating current source of electric supply and a divided circuit to which it is applied having a furnace coil providing inductance in 65 one part of the circuit and a capacity in the other, the two parts of the divided circuit forming a circuit in approximate tune with the source of supply and free from discharge gap interruption.
15. A high frequency high tension alternating current source of supply, a heating coil providing inductance and adapted to heating a resistor and an approximately resonant circuit including the heating coil and a capacity, to which the source of supply is 70 connected.
16. In a heating system, a heating system containing capacity and an inductor heating coil and supply current therefor maintaining the amplitude of the discharge from 80 said capacity and with the frequency of which the supply circuit for the heating system is in approximate tune.
17. An electric furnace circuit having initially a negative reactance.
18. An electric heating device whose circuit contains a negative reactance, in combination with supply current therefor having a positive reactance.
19. A high frequency current electric furnace having a secondary charging circuit 90 provided with a negative reactance.
20. A furnace, an oscillation discharge circuit therefor, including a condenser and a high tension charging circuit therefor 95 which, with the condenser, tends to give a leading current.
21. An electric heating device whose circuit naturally has a negative reactance in combination with positive reactance compensating therefor to produce unity power factor in the supply circuit.
22. The method of applying energy by electromagnetic induction, to be converted into heat within a removable resistor mass, 100 which consists in passing high frequency currents about the resistor free from interlinkage of a transformer magnetic circuit with the electric circuit.
23. The method of applying energy by 110 electromagnetic induction to be converted into heat within a resistor mass which consists in passing high frequency current through a conducting coil surrounding the resistor to be heated.
24. The method of transferring electric energy into a mass so as to become thermal energy therein by electromagnetic induction which consists in circulating high frequency currents in inductive relation to the mass, 120 free from interlinkage of a transformer magnetic circuit with the electric circuit.
25. The method of furnace heating which consists in inducing electric current flow within the pool directly from electric current flow outside the pool, as distinguished from linking the material in the pool and the outside current by a transformer magnetic circuit.
26. The method of heating electrically 130

conducting substances not capable of effectual magnetization which consists in inducing electric currents therein from a current carrying coil directly, without interposition of a transformer magnetic circuit.

27. The method of heating a pool which consists in utilizing the body of the pool as a secondary for a high frequency current primary.

10 28. The method of heating material in liquid condition which consists in discharging a condenser through a coil surrounding the material.

15 29. The method of heating molten metal which consists in setting up closed circuits of electric current flow in the metal having period like that of free oscillation currents.

20 30. The method of heating molten metal which consists in placing the metal in a furnace pool in inductive relation to a conducting coil and passing through said coil current discharged from a condenser.

25 31. The method of stirring a pool of electrically conducting material having a free upper surface which consists in electrically producing considerable substantially radial pressure in the body of the pool, with consequent upward movement of the center of the pool and downward movement of the material in proximity to its circumference.

30 32. The method of stirring molten metal which consists in placing a conducting coil in inductive relation to the metal and transmitting through said coil electric current having high frequencies.

35 33. The method of stirring a liquid pool by electromagnetic action which consists in setting up in it currents in closed circuits having the same periodicity as free oscillatory currents.

40 34. The method of stirring a molten pool which consists in electrically forcing molten metal from the outer part of said pool between the top and the bottom inwardly in substantially radial planes with resultant flow of metal from the other parts of the pool to take the place of the molten metal displaced.

45 35. The method of stirring a furnace resistor which consists in circulating currents about the circumference of a molten resistor to produce electromagnetic circulation from the more highly heated circumference toward the middle.

50 36. The method of stirring a furnace pool which consists in circulating high frequency current through it near its perimeter.

37. The method of stirring a mass of electric conducting molten or otherwise liquid material which consists in inducing flow of high frequency current through it in closed substantially horizontal circumferential paths near its perimeter.

60 38. The method of obtaining unity power factor in an electric heating circuit con-

nected with a supply having a positive reactance which consists in providing more than enough negative reactance in the heating circuit to overcome the positive reactance of the supply and balancing the two by positive reactance.

39. The method of improving the power factor of an electric furnace connected with a supply circuit having a lagging current which consists in providing the furnace with a negative reactance to take a leading current and balancing the two reactances against each other to improve the power factor.

40. The method of improving the power factor in electric furnace operation which consists in connecting a furnace having negative reactance in its circuit with a current supply having positive reactance and balancing the reactances to produce unity power factor by introducing a reactance substantially equal to the difference of the reactances of the furnace and supply and having an opposite sign from that of their difference.

41. The method of applying energy by electromagnetic induction to be converted into heat within a resistor mass, which consists in passing high frequency oscillation currents about the resistor and maintaining the amplitude of the oscillations.

42. The method of applying energy by electromagnetic induction to be converted into heat within a resistor mass, which consists in supplying high frequency current to a circuit in approximate tune therewith containing a heating coil and containing also a condenser and thereby passing current of the same frequency through the coil to inductively heat the resistor.

43. The method of inductively transferring energy from a coil to a resistor to be heated which consists in placing the coil in a circuit with a condenser, the circuit being free from discharge gap interruption, and applying high frequency alternating current to the circuit at two points at opposite extremities of the condenser, so placed, and with such circuit constants as to approximately tune the condenser-coil circuit.

44. The method of forming and applying powerful inductive heating currents which consists in discharging currents from a condenser through a heating coil and maintaining the amplitude of discharge and at the same time supplying energy to the circuit by an outside electric circuit with which the circuit through the coil is in approximate tune.

45. The method of increasing the efficiency of oscillation current discharge for electric heating which consists in providing high frequency alternating current supply for the heating circuit and at the same time maintaining the amplitude of the oscillations within the heating circuit and rendering

the oscillations continuous by approximately tuning the heating circuit to the supply.

46. The method of furnishing large currents of high frequency for heating purposes which consists in providing a negative resistance and an inductor heating coil in the heating circuit and in supplying energy thereto from an outside source of high frequency alternating current at opposite terminals of the inductor.

47. The method of obtaining high current values out of phase with the electromotive force in a heating circuit while maintaining the current in the supply circuit in approximate phase with its electromotive force which consists in forming the heating circuit as a divided circuit containing inductance within the heating coil and also a condenser and in applying high frequency alternating current supply across the condenser.

48. The method of correcting the phase relation between the electromotive force and

current in a generator circuit feeding current through a furnace inductor coil having a positive reactance which consists in utilizing a bridging negative reactance to compensate for the positive reactance of the inductor coil and to secure unity power factor.

49. The method of securing a high current through a furnace inductor circuit with low current and high power factor in an alternating current supply circuit therefor, which consists in placing the inductor furnace coil in one branch of a divided circuit fed by the supply circuit and including capacity in the other branch thereof, whereby the current in the divided circuit is displaced with respect to its electromotive force to varying degrees depending upon the energy consumed in the furnace coil and approaching 180° as the energy consumed thereby approaches zero.

EDWIN F. NORTHRUP.
